ROOFING TILE

Fred H. Kawamura, Honolulu, Territory of Hawaii

Application September 15, 1937, Serial No. 164,041

1 Claim. (Cl. 108—10)

This invention relates to roofing tiles and has for an object to provide a tile having substantially rectangular notches at one pair of the diametrically opposite corners to promote ease of laying and to promote lap joints in that when laid in courses the upper portion of a tile fits into a notch in a tile of the next upper course and the lower portion of the tile fits into a notch of a tile in the next lower course.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification,

Figure 1 is a plan view of a portion of a tiled roof constructed in accordance with the invention.

Figure 2 is a longitudinal sectional view taken on the line 2—2 of Figure 1.

Figure 3 is a cross sectional view taken on the line 3—3 of Figure 1.

Figure 4 is a cross sectional view taken on the line 4—4 of Figure 1.

Figure 5 is a detail perspective view of one of the tiles.

Figure 6 is a detail perspective view of a tile ridge.

Referring now to the drawing in which like characters of reference designate similar parts in the various views, the central portion of the tile 10 is flat and from thence the two sides 11 and 12 slope upwardly and outwardly in an angle of 25 degrees to the central portion. The side 11 is provided with a reversely sloped wing 13 of less width than the width of the side 12, the wing sloping at an angle of about 25 degrees as best shown in Figure 5.

Two of the diametrically opposite corners of the tile are cut away to provide notches 14, and 15. The notch 15 in one corner of the tile, that is in the side 12, is less in width than the width of the wing 13 and the notch 14 in the other corner of the tile, that is at the end of the wing 13, is the same in width as the width of the wing 13. A nail hole 16 is formed in the center portion of the tile near one end edge thereof.

The tiles of the first layer at the eaves will be devoid of the notch 15 in the side 12 to produce a right angular edge as shown by the dotted lines at 17 in Figure 5.

For a gabled roof, where the sides of the tile must form a straight edge from the ridge to the foot of the roof, a slightly different tile must be used, that is, the tile will be constructed as shown in Figure 5 with the exception that the

wing 13 will be dispensed with in tile on the left side of the roof and the notch 15 will be dispensed with in tile on the right side of the roof, making right angular edges as shown by the dotted lines at 17 in Figure 5.

In Figure 6 there is shown a ridge tile 18 which is arcuate in cross section and is provided with an offset extension 19 which fits over the end of the next adjacent tile. The tile is provided with a nail hole 20 at the end opposite the offset 10 extension 19.

In laying the tile, the layers are started from the lower end of the roof, the upper portion of the wing 13 of one tile fits into the notch 15 in the side 12 of a tile in the next upper course 15 and the lower part of the side 12 of the tile fits into the notch 14 in the wing 13 of a tile in the next lower course. In this manner an overlap of about six inches will be provided at the joint, made up of the wing 13 and side 12 of contiguous 20 tiles, as best shown in Figure 1.

It is not necessary to nail every tile to the wood sheathing 21 because the interlocked tiles, laid as above described, will not slide, and the weight of the layers holds the tiles in place. 25 Furthermore it does not require a solid wooden sheathing over the rafters 22 since the tile can be laid over the usual single sheathing, shown at 21, spaced several inches apart.

It will be further pointed out that the tiles 30 of the first layer at the eaves are each provided with an overhang 23 in addition to being constructed as previously described.

From the above description it is thought that the construction and operation of the invention 35 will be fully understood without further explanation.

What is claimed is:

A roofing tile having a flat central portion, 40 side flanges diverging from one face of the central portion at the longitudinal edges of the central portion, one side flange being provided with a wing sloped oppositely to the flange and of less width than the width of the other side 45 flange, there being a tile locking notch formed in one side flange, there being a tile locking notch formed in said wing diagonally opposite the notch formed in said side flange and being less in width than the width of the wing, the arrangement being such that when the tiles are laid in courses the upper portion of the wing of a tile is adapted to be received in the notch in the side flange of a tile in the next upper course, and the lower part of the side flange of the tile is 50 adapted to fit into the notch in the wing of a tile in the next lower course to provide lap joints.
